SHOWER AND TUB DIVERTER VALVE HANDLE

Stephen A. Young, Delphi, Ind.

Application June 23, 1949, Serial No. 3,470

Term of patent 14 years

(Cl. D4—3)

To all whom it may concern:

Be it known that I, Stephen A. Young, a citizen of the United States and a resident of Delphi, county of Carroll and State of Indiana, have invented a new, original, and ornamental Design for a Shower and Tub Diverter Valve Handle, of which the following is a specification, reference being had to the accompanying drawing, forming part thereof.

In the drawing Fig. 1 is a top plan view of a shower and tub diverter valve handle showing my new design. Fig. 2 is a side elevation thereof. Fig. 3 is a bottom plan view.

I claim:

The ornamental design for a shower and tub diverter valve handle, as shown.

STEPHEN A. YOUNG.
